UNITED STATES PATENT OFFICE.

JAMES J. HANNON, OF LOGANSPORT, INDIANA.

PISTON-PACKING FORMER AND REPLACER.

No. 853,973.

Specification of Letters Patent.

Patented May 21, 1907.

Application filed March 18, 1907. Serial No. 363,040.

To all whom it may concern:

Be it known that I, JAMES J. HANNON, a citizen of the United States, residing at Logansport, in the county of Cass and State of Indiana, have invented certain new and useful Improvements in Piston-Packings Formers and Replacers, of which the following is a full, clear, and exact specification.

This invention relates to a device for forming a leather packing upon a piston and maintaining the finished form of such packing while the piston is inserted in its cylinder. As is well known, this form of piston packing is in general use, notably for packing the pistons of cylinders in air brake systems, and the packing requires frequent renewal and replacement with the piston in the cylinder, which is found difficult, as the springy edges of the new packing leather will not enter the cylinder readily.

One of the objects of my invention is to afford means to form the packing into proper shape upon the piston and to retain it in position thereon for ready insertion in the cylinder.

With this and other objects in view, the invention consists in the device and resulting combinations to be described in detail in this specification and specifically pointed out in the appended claims.

Referring to the accompanying drawings, wherein similar letters of reference are used to indicate corresponding parts in each of the several views: Figure 1 is a view in longitudinal section of an air brake cylinder, the cylinder head being shown in side elevation, detached, and the piston being shown as about entering the cylinder and embraced and guided by a device embodying my invention; Figs. 2 and 3 are views in perspective, detached, of the parts of my packing former and replacer; Fig. 4 is a side elevation of a device embodying my invention, the parts being assembled; Fig. 5 is a diametrical section thereof; Fig. 6 is an elevation, looking at the mouth of the forming end of my device; Figs. 7 and 8 are, respectively, elevations of the parts of my device, showing the means for interlocking the parts.

In the drawings, (Fig. 1), I have shown a cylinder 1, with the head 2, the piston rod 3 detached, and the piston, 4, 4^a, about entering the cylinder with a newly applied packing 5, 5^a, the piston replacing ring being shown as snugly embracing the piston and packing and seated on the end flange of the

cylinder in position for inserting the piston in the cylinder. The piston head is of common type, comprising a main disk 4 secured to the piston rod and a clamping disk 6^a, of less diameter, bolted to disk 4, the packing leather being cut in the form of a circular washer, the body 5 of which is tightly clamped between the disks 4 and 4^a of the piston, the edge 5^a being turned up against the periphery of disk 4^a, and snugly fitting the bore of the cylinder.

Packings of this character wear rapidly and require frequent replacement, especially when subjected to the hard and constant service of air brake systems, and much difficulty is experienced and time consumed in inserting within the cylinder a piston fitted with a new packing which will best fulfil its intended purpose as the cupped edge 5^a springs outward and impinges against the end of the cylinder. To overcome this difficulty I have devised a former and replacer for these packings, consisting of a three-part implement, comprising a former A (Fig. 3) to crimp or cup the packing upon the outer disk 4^a of the piston and a replacer B (Fig. 2), removably secured to the former A, (Figs. 4 and 5), to hold the skirt or edge 5^a of the packing upon the piston and guide it into the cylinder.

The former A is an annular body of metal or other desired material, the interior diameter of which at its inner end *a* coincides with the bore of a cylinder of given size, flaring thence outwardly to its outer end or mouth *a'*, as shown. Externally, the former A is provided at diametrically opposite points with hand grips *a²*, and at suitable points with lugs *a³* (four being shown) hooked, as best shown in Fig. 3, to detachably engage the replacer B. The replacer also consists as a whole of an annular body, its interior being cylindric and of a diameter to accurately match the inner end *a* of the former and, therefore, the cylinder. The replacer is made in two parts and, as shown, these comprise each a half-annulus, the two being united by a hinge joint *b* and the free ends being provided with lugs *b¹*, *b²*, having registering perforations to receive a thumb screw C or equivalent means to lock the hinged parts of the replacer securely together to form a rigid ring. The ends of the replacer are shown as outwardly flanged (see Fig. 2), the outer flange *b³* or that meeting the former A being notched to receive the hooked lugs

a^3 of the former A, whereby the former and replacer may be locked together, and being provided with guide studs b^4 to engage the cylinder flange, as will be explained.

5 In practice, to remove a worn packing and replace it with a new one, the piston rod is temporarily locked to the cylinder head 2 by a pin 6, or other suitable means, such as a wedge driven between the rod and head, and the head 2 and rod and piston removed from the cylinder. The disk 4 and the worn packing are then removed and the replacer and former, secured together, are passed over the disk 4 and onto the piston rod. A new packing is now secured by disk 4^a and the former A drawn over the piston, crimping or cupping the part 5^a of the packing. When the inner edge of the former reaches the edge of the packing, it is unlocked from the replacer by giving it a partial turn to bring the hooked lugs opposite the notches of the flange b^3 and removed, thus leaving the replacer closely embracing the skirt of the packing. The piston and replacer are now advanced to the open end of the cylinder and the guide studs b^4 engaged in the bolt holes of the cylinder flange (see Fig. 1), when the piston may be readily thrust through the replacer into the cylinder, the replacer removed from the position it has assumed between the cylinder and cylinder head by removing the thumb screw and opening the parts of the replacer so they will pass the piston rod, when the cylinder head is again bolted to the cylinder and the pin 6 removed.

It is not essential that the replacer B be given the specific form shown, but it is required that the interior diameter correspond with the piston cylinder to be fitted and that it may be removed from between the cylinder and cylinder head after the piston with the new packing is inserted within the cylinder, and I intend that my claims cover broadly a device capable of the function described. Moreover, the replacer B may in some instances be used independently of the former A, for instance, with thin, readily formed washers or packings for small air pump cyl-

inders and the like, as the leather in such case may be readily formed cup-shape by hand, without the former, and the replacer be used to insert the piston and renewed packing in the cylinder.

Having thus fully described my invention, what I claim as new and desire to secure by Letters Patent of the United States, is:

1. A piston replacer consisting of a two part annulus having a diameter corresponding with a given cylinder, the parts of the annulus being hinged at one point and provided with connecting means at an opposite point, and lugs on the face of said annulus adapted for registering with openings in the cylinder flange.

2. A piston packing former and replacer comprising an annulus with flaring mouth, and inner end having a diameter corresponding with a given cylinder, and a separable annulus having the same interior diameter as the inner end of the former and detachably connected thereto.

3. A piston packing former and replacer comprising an annulus with a flaring mouth and an inner end having a diameter corresponding with a given cylinder and an annulus having the same interior diameter as the inner end of the former and detachably connected thereto.

4. A piston packing former and replacer comprising an annulus with a flaring mouth and an inner end having a diameter corresponding with a given cylinder, a separable annulus having the same interior diameter as the inner end of the former, lugs on said first named annulus adapted to engage recesses in the separable annulus, whereby the two may be detachably secured together, substantially as described.

In testimony whereof I have signed my name to this specification in the presence of two subscribing witnesses.

JAMES J. HANNON.
